US0D1080217S

(12) **United States Design Patent** (10) **Patent No.:** **US D1,080,217 S**
Lenney (45) **Date of Patent:** **** Jun. 24, 2025**

(54) **UNIVERSAL GUTTER GUARD CLEANING BRUSH**

(71) Applicant: **Gutterglove, Inc.**, Franklin, TN (US)

(72) Inventor: **Robert C Lenney**, Lincoln, CA (US)

(73) Assignee: **GUTTERGLOVE, INC.**, Franklin, TN (US)

(**) Term: **15 Years**

(21) Appl. No.: **29/873,565**

(22) Filed: **Apr. 3, 2023**

Related U.S. Application Data

(60) Division of application No. 29/757,146, filed on Nov. 3, 2020, now Pat. No. Des. 999,534, which is a continuation of application No. 15/837,767, filed on Dec. 11, 2017, now Pat. No. 10,827,821.

(57) **CLAIM**

The ornamental design for a universal gutter guard cleaning brush, as shown.

DESCRIPTION

FIG. 1 is a bottom plane view of an embodiment of a universal gutter guard cleaning brush showing my new design;

FIG. 2 is a front plane view thereof;

FIG. 3 is a top plane view thereof;

FIG. 4 is a right plane view thereof;

FIG. 5 is a rear plane view thereof; and,

FIG. 6 is a left plane view thereof.

1 Claim, 12 Drawing Sheets
